UNITED STATES PATENT OFFICE.

HERMAN L. STRONGSON, OF BROOKLYN, NEW YORK.

ELECTRIC-LAMP SOCKET.

Application filed December 4, 1922. Serial No. 604,676.

To all whom it may concern:

Be it known that I, HERMAN L. STRONGSON, a citizen of the United States, residing at Brooklyn, in the county of Kings and 5 State of New York, have invented certain new and useful Improvements in Electric-Lamp Sockets, of which the following is a specification.

This invention relates to electric lamp 10 globe sockets and the like, and more particularly relates to improvements in multiple or cluster globe push plug sockets for plug-in connection with slotted type or plug-in type wall receptacles.

15 An object of this invention is to provide a device having on one end plug-in contacts or improved jack-blades which make secure mechanical and electrical connection with slotted type wall receptacles, and on the 20 other end there is provided the usual screw receptacle, one or more, for receiving threaded plug connectors or lamp globes and the like; and it is an object to improve the construction of electric lamp sockets for 25 use in connection with plug-in type wall receptacles, and also to produce lamp sockets consisting of few parts which are inexpensive to produce and are simple and easy to 30 assemble, possessing an ornamental appearance, and more durable than present day sockets.

This invention is a modification or improvement on the socket structures of my previous patent applications Serial Numbers 35 445,770 and 479,804.

The accompanying drawing illustrates an exemplary embodiment of my improved lamp socket serving to explain the principle of the invention, the construction of which 40 may be adapted to various modified structures to better suit the needs of manufacturers and the varying uses of the trade.

Figure 1 illustrates a perspective view of the socket; and Figure 2 illustrates a cross 45 sectional view thereof.

Figures 3 and 4 illustrate the socket partly disassembled with the metal contact parts placed in position on each respective body section and made ready to assemble by 50 putting the two parts together to form a completed lamp socket.

Figure 5 illustrates a perspective view of a modified form of my invention wherein I 55 employ a smooth bore or non-threaded socket receptacle in which is employed an

improved corrugated or threaded contact member to hold the lamp globe and transmit current thereto.

Figure 6 is a view of the improved stamped or punched metal conductor as it 60 appears before being placed in the socket casings to plainly show the resilient contact forks.

A push plug socket constructed in accordance with the principles of this invention 65 utilizes single one-piece metal punchings as conductors for transmitting current from a current feed fixture or wall receptacle to one or more lamp globes or appliance connections held in the device; and the socket is 70 characterized by the simplicity of parts, and by the ease with which the contact members and body parts are assembled to produce a rugged serviceable long lasting device; and I am enabled to economically produce 75 plural or multiple lamp sockets because of the one-piece, jointless, and continuous contact structure which embodies a jack-blade connector extending into one or any number of lamp receptacles affording side and 80 center contact without advertizing to the use of solder, screw, or rivet-made connections.

For convenience in the manufacture of this improved lamp socket, I make the body or casing thereof of insulating material and 85 preferably mold it into mating half-sections which are secured together by any appropriate means with the metal contact parts anchored therebetween. The body sections are made with central web portions 10 com- 90

paratively thin in structure, so that the webs or walls 10 when clamped together present a trim neat appearance and not involving an excessive amount of material in the construction thereof. A boss or flat disc 11 is integrally formed on the web 10 and affords an abutting face or rest which lies in 95 contact with the face of a wall plug or other current supply receptacle to which this improved lamp socket is attached. Lamp globe

100 sockets 12 are formed in the insulating body, each body section carrying its complementary section and affording a completed socket receptacle when the two body sections are joined together. Any suitable

105 number of globe receptacles 12 are made in the body for, as will be understood, my improved construction, and particularly the improved contact parts, can be so formed 110 by the stamping and punching process so

that the said improved contacts may be made to run to any desired number of receptacles. The adjacent faces of the body sections are molded substantially flat or plane 5 excepting that each section is preferably constructed with a shallow groove in its plane face for the reception of a stamped metal contact part.

I employ a pair of improved one-piece 10 conductor members which are of integral construction and jointless or continuous, there being no riveted, screwed, or solder-made connections or operations. One of the conductors is utilized as a center contact 15 member which projects into and terminates at the bottom of each receptacle 12, and possesses a jack-blade plug-in connector integral with the said conductor; and the other conductor member is utilized as a side contact, being disposed along the wall of each 20 socket parallel to the axis thereof with a similar integral jack-blade; and the two jack-blades afford a parallel electrical plug-in connecting means. The center contact 25 member 14 is, in this particular embodiment, made substantially T-shaped; and the side contact member 15 is made with a plurality of substantially U-shaped, furcated, or forked contact members 16. Each conductor 30 member 14 and 15 is punched or stamped from sheet metal with a jack-blade 17; and the two jack-blades project parallel from the socket boss 11 when assembled. An insulating sheet 18, such as fiber or other suitable 35 material, is likewise punched from sheet material and rests in the body groove adjacent to and in contact with one of the conductor members as shown in Figure 3. This insulator 18 affords positive separation and 40 insulation between the two closely spaced conductors 14 and 15.

The exposed center contact ends of the conductor 14 are preferably turned over on the end to provide a center contact having 45 an effective engaging area so that when an electric light bulb or a screw plug, or other wiring devices, are screwed into the receptacle 12 there is established positive electric center contact. The conductor 15 is similarly stamped or punched from sheet material with the forked arms 16 cut comparatively narrow so as to impart a perceptible degree of springiness and yieldability, the purpose of which is to cause the oppositely 55 disposed contact fingers 16 to lightly rub and press the metal screw shell of an electric light globe or other plug when screwed into the receptacle, thereby establishing positive side electrical contact. The grooves 20 made in the wall of the socket section 12 are preferably deeper than the width of the contact fork 16 so this fork may yield and press back into the grooves 20 when a plug or globe is screwed into the receptacle.

65 My improved lamp sockets have one, two

or more receptacles 12 which are preferably molded with screw threads as shown in the first several figures of the drawing; and the contact fork 16 is stamped or punched with a die which is corrugated to cut and form 70 threads 21 on the internal edges of the contact fork 16. When the contact fork 16 with its integral stamping 15 and jack-blade 17 are placed in the groove 20, the corrugations 21 match with the threads of the socket 12 75 thereby forming a continuous and uninterrupted screw thread structure; and it is significant that the said corrugations or metal threads 21 of the contact fork are perceptibly exposed in the threaded receptacle 80 surface by projecting slightly above the pitch of the threads. This arrangement provides positive threaded contact against the metal shell of a globe or plug when it is screwed into the receptacle. 85

Figure 5 illustrates a modified form of the invention utilizing the same conductor and contact member as hereinbefore described except that I have varied the internal receptacle construction thereof. In this 90 modified structure, I utilize the thin sheet metal corrugated or threaded contact fork for two purposes, namely, to afford positive electrical contact, and to securely hold an electric lamp globe or other device in the socket 95 receptacle. This improved socket receptacle 25 constitutes a plain bore or a non-threaded structure not possessing screw threads. The corrugations 21 on the inner thin edge of the contact fork 16 are sufficiently exposed above 100 the surface as to effect positive threaded gripping connection with a lamp base or other device inserted in the receptacle 25.

Figure 5 also illustrates the manner in which receptacles 12 or 25, threaded or 105 smooth bored as the case may be, are angularly disposed in relation one to the other. When it becomes desirable on the part of the manufacturer to furnish the market with different forms or angles of sockets, he 110 can readily mold the body sections with receptacles leading off in any direction desired; and accordingly, he varies the shape and position of the contact forks in the same manner without departing from the principle 115 of the invention.

This improved socket is economical to produce because of its inherently simple contact members and small number of parts involved; and it is to be observed that the thin flat conductors are disposed between the thin flat webs 10 and 10 which minimizes in materials used and makes for trimness and neatness in structural appearance. There are no riveted, soldered or screw made 120 connections to be fitted and assembled and subsequently become loosened to the point where short circuits or arcing occur. The two contact parts are readily placed in their 125 respective grooved bodies, the insulator is 130

applied, and then the two body sections are secured together with eyelets or rivets 26.

What I claim is:

1. A new article of manufacture comprising a stamping punched from sheet metal, flexible spring fingers integral with the stamping and internally corrugated to make screw-threaded contact parts, and a jack-blade integral with the stamping to form a plug-in contact.
2. Improvements in electric globe sockets comprising a body having socket receptacles, a pair of parallel jack-blade contacts projecting from the body, contact fingers integral with one of the jack-blades and extending along the wall of the receptacles to form side contacts, said contact fingers being internally corrugated to make screw-threaded contact engagement with lamp globes and the like inserted in the receptacle, and branches integral with the other jack-blade forming center contacts in the receptacles.
3. Improvements in lamp sockets comprising a body member having globe receptacles, sheet metal contact blades disposed edgewise along the wall of the receptacles and being flexible to make spring contact, corrugations made in the edges of the said flexible blades to simulate screw threads, a jack-blade punched integrally with the aforesaid contact blades and projecting from the body, a center contact part secured at the bottom of receptacles, and another jack-blade integral with the center contact part and projecting from the body parallel to the first named jack-blade.
4. Improvements in lamp sockets comprising a body having globe receptacles, a furcated contact member with its furcations oppositely disposed within the receptacles to engage a lamp or other device inserted in

the receptacle, a jack-blade integral with the contact member and projecting from the body, a contact member extending from the center of the other receptacles, and a jack-blade made integral with the last named contact member and projecting from the body in a parallel relation with the first jack-blade to form a plug-in connector.

5. Electric lamp sockets comprising a body made of insulating material, smooth bore non-threaded socket receptacles for the reception of lamp bulbs and the like, a metal stamping in the form of a fork disposed in the socket receptacles, corrugations made on the stamping simulating screw-threads which project above the smooth surface of the receptacle to form positive electrical and anchoring connection with a lamp base or other device screwed into the receptacle, a center contact, and parallel jack-blades integral with the stamping and center contact.

6. Improvements in electric globe sockets comprising a body having socket receptacles, a pair of jack-blade contacts projecting from the body, a contact fork integral with one of the jack-blades and being disposed in the receptacle with the prongs thereof diametrically opposed, and branches stamped integral with the other jack-blade forming center contacts in the receptacle.

7. A new article of manufacture comprising a forked contact member with the prongs thereof threaded and made flexible to form yieldable contacts, and a jack-blade made integral with the member.

In testimony whereof I affix my signature this 29 day of November 1922, in the county of New York, city of New York, and State of New York.

HERMAN L. STRONGSON.
